UNITED STATES PATENT OFFICE.

MYRON D. SHIVERICK, OF ALBANY, NEW YORK, ASSIGNOR TO WILLIAM E. MILBANK, OF ALBANY, NEW YORK.

COATING OR ENAMELING APPARATUS.

No 921,292.

Specification of Letters Patent.

Patented May 11, 1909.

Application filed October 24, 1908. Serial No. 459,309.

To all whom it may concern:

Be it known that I, MYRON D. SHIVERICK, a citizen of the United States, residing at Albany, county of Albany, New York, have 5 invented a new and useful Improvement in Coating or Enameling Apparatus, of which the following is a specification.

My invention relates to an apparatus or machine for covering the surfaces of tubes, 10 rods, lengths of wire or like articles with japanned or baked enamel. Such enameling is useful to protect the tube or the like from oxidation, or, particularly, to electrically insulate it.

15 The object of my invention is to cheaply and thoroughly coat the article with a hard elastic covering, so that it may be bent without injury to such covering.

20 While my machine may be used to enamel articles of different sorts, and may vary widely in its form, I will illustrate it as applied to the coating of tubes.

25 In the drawings, Figure 1 is a side elevation of a preferred form of my device; Fig. 2 is a top plan view of the same; Fig. 3 is an enlarged detail, in elevation and top plan, of the feed tube tip shown in Fig. 1; Fig. 4 is a top plan view of a modified form of my device; Fig. 5 is a side elevation of another 30 modification.

35 Referring first to Figs. 1, 2 and 3 of the drawings, 11 designates a base, on which are mounted bearings 12 and 13, which support a rod 15, threaded at one end to engage a tension screw 16, by which the rod 15 is maintained in taut position. Also mounted on the base 11 is a driving device, shown as a motor 17, which turns a friction wheel 18, against which bears a second friction wheel 19, rotatable on the rod 15 and carrying a 40 tube engaging device, shown as a chuck 20. The base 11 also carries adjacent its opposite ends two pairs of standards 21, 22, which form bearings for pulleys 23, 24, on which 45 runs a belt 25 of steel, iron or the like. On the shaft 26 of one of the pulleys 23 is a friction wheel 27, which is rotated by contact with the face of the wheel 18. Running on a track 28 on the base 11 is a truck or carrier 29, which carries the baking oven 30, which 50 consists of a closed box having apertures 31, 32 at its opposite ends for the passage of the rod 15 and the tube carried thereon. In the oven 30 is an electric heating device, consisting

of two parallel insulating rods 33 and a strip 34 of high resistance metal spirally wound thereon and connected with a suitable source of electric energy. Mounted at the forward end of the carrier 29, closely adjacent the end of the heater oven 30 is a feeding device 35, 60 consisting of a suitably supported receptacle 36, from which leads a bent tube 37 carrying a tip 38, the mouth of which is in the form of a narrow elongated slot 39; see Fig. 3. Also mounted on the carrier 29 is an electro-magnet 40, the poles of which contact, or practically contact, with the metal belt 25.

The operation of the machine just described is as follows: A tube 41 is slipped over the rod or mandrel 15, which is then 70 drawn taut, by the screw 16, the tube being held by the chuck or like engaging device 20, with its free end contacting with the feed tip 39. The oven 30 being previously heated by current passing through the resistance 34, 75 the motor 17 is started. Through the action of the friction wheels 19 and 27 the tube 41, which is to be enameled, is rotated and the oven 30 is caused to traverse the base 11 from right to left of the drawing by switching 80 current through the coils of the magnet 40, the poles of which then adhere to the belt 25. At the same time the stopper 42 in the receptacle 36 is raised, so that the liquid or viscous enamel flows by gravity or by capillary 85 action on to the lower side of the tube 41. In practice, I prefer to make the slot 39 so narrow that the enamel does not spontaneously flow therefrom, but is retained by capillarity 90 therein, so that it is wiped off the tip 38 and on to the tube 41 by their moving contact. As the tube is rotating and the tip 38 is being moved longitudinally thereof, the enamel will be applied in a spiral to the tube.

It is obvious that the relative rates of 95 movement of the tube and the carrier 29 are so arranged that the edges of the spirally deposited enamel meet or slightly overlap, whereby the entire surface of the tube is covered. The enamel feeding device being in 100 close juxtaposition to the oven 30, the coated portion of the tube passes immediately into the oven through the aperture 31, and the baking operation begins.

When the oven has reached its final position, the tube is completely enameled, when 105 the motor 17 is stopped, the magnet 40 cut out, the carrier 29 run back, and the tube re-

moved from the mandrel 15, so that the machine is ready for a second operation. It is clear that if the tube 41 were not placed on the rod 15, the rod itself, or any rod so placed, could be enameled in like manner.

In the fourth figure of the drawings, I have omitted many parts which are similar to the corresponding parts already described. The bearings 52, 53 are adapted to carry a plurality of rods 15, shown as arranged side-by-side, and each held taut, as before, by a set-screw 16. Each rod passes freely through a chuck 20, adapted to engage a tube 41, slipped over the rod, the chucks being simultaneously rotated by intermeshing gears 54, driven, as before, by a motor as 17. The carrier 29 supports a number of feeding devices 35 corresponding to the tubes 41, here shown as five. In like manner, the oven 60 differs from that first described only in having a corresponding plurality of apertures at each end to pass the tubes 41. It is obvious that, except for its capacity, the operation of the machine will be unchanged.

As it is only necessary to the operation of my invention that the tube or other article to be coated should have a spiral, *i. e.*, a combined rotary and longitudinal, movement relative to the liquid feeding means, and a longitudinal, though preferably spiral, movement through the heating chamber or oven, I have shown in Fig. 5 another modification of my machine. Standards 72, 73 support, as before, a rod 15 provided with tightening screw 16. The chuck 20, which holds the tube 41, is mounted at the end of a hollow lead-screw 75, these last-named three parts being slipped over the rod 15. In the lead-screw 75 is cut a keyway 76, into which engages a key on the friction wheel 77, driven as before. The wheel 77 is shown as held between the arms of a forked support 78, in at least one arm of which the screw 75 is threaded. The feeding device 35, as well as the baking oven 79, is stationary and mounted directly on the base 11. It is obvious that the tube 41 will in this construction be fed spirally above the feed aperture 38 and through the oven 79, so that the practical operation and result of the machine will be unchanged.

It is clear that many mechanical changes other than those shown may be made in my apparatus, without departing from the spirit of my invention; and that parts of the device may be employed without the others. I do not therefore wish to limit my invention, except as set forth in the appended claims.

What I claim is:

1. An enameling machine comprising means for supporting and rotating an article to be enameled; a heating oven; and means for giving such article and said oven relative longitudinal movement.

2. An enameling machine comprising

means for supporting an article to be enameled in a substantially horizontal position; means for rotating such article; a heating oven; and means for giving such article and said oven relative longitudinal movement.

70

3. An enameling machine comprising means for supporting and rotating an article to be enameled; an electrically heated oven; and means for giving such article and said oven relative longitudinal movement.

75

4. An enameling machine comprising means for supporting and rotating an article to be enameled; a heating oven provided with apertures for the passage of such article therethrough; and means for moving said oven longitudinally of such article.

80

5. In an enameling machine, a heating oven; a carrier on which said oven is mounted; a belt movable adjacent said carrier; and magnetic means for detachably connecting said belt and said carrier for moving the latter.

85

6. In an enameling machine, a heating oven; a carrier on which said oven is mounted; a belt of magnetic metal movable adjacent said carrier; and a magnet mounted on said carrier for detachably connecting it with said belt.

90

7. In an enameling machine, means for supporting and rotating an article to be enameled; means for applying a liquid or viscous enamel to such article; subsequently operative means for heating such articles; and means for giving such article and said applying means relative longitudinal movement.

95

8. In an enameling machine, means for supporting an article to be enameled in a substantially horizontal position; means for rotating such article; means for applying a liquid or viscous enamel to such article; subsequently operative means for heating such articles; and means for giving such article and said applying means relative longitudinal movement.

100

9. In an enameling machine, means for supporting and rotating an article to be enameled; means for applying a liquid or viscous enamel to such article; and means for moving said applying means longitudinally of such article.

110

10. In an enameling machine, means for supporting an article to be enameled; and means, including a narrow elongated feeding slot, for supplying a spiral coating of liquid or viscous enamel to such article.

115

11. In an enameling machine, means for supporting an article to be enameled; and means, including a feeding tip supported beneath such article, for supplying a spiral coating of liquid or viscous enamel thereto.

125

12. An enameling machine comprising means for supporting and rotating an article to be enameled; enamel applying means; a heating oven; and means for giving such

130

article longitudinal movement relatively to said applying means and said oven.

13. An enameling machine comprising means for supporting and rotating an article 5 to be enameled; a carrier movable longitudinally of such article; and enamel applying means and a heating oven mounted in juxtaposition upon said carrier.

14. An enameling machine comprising 10 means for supporting an article to be enameled; means for supplying a spiral coating of liquid or viscous enamel to such article;

and a heating oven in juxtaposition to said coating means for baking such enamel.

15. An enameling machine comprising 15 means for supporting in parallel relation and for rotating a plurality of articles to be enameled; a heating oven; and means for giving such articles and said oven relative longitudinal movement.

MYRON D. SHIVERICK.
